TEST DRILL

Frank C. Sturges, Dormont, Pa.

Application November 17, 1937, Serial No. 174,914

3 Claims. (Cl. 255—1)

This invention relates to test drills, and more particularly to an improved apparatus for drilling through the overlying strata of the earth to secure test samples of the earth formation.

5 When a building or any other structure is to be erected having a foundation extending into the strata overlying bed rock, it is extremely important to have an accurate knowledge of the type and character of the various formations of the 10 earth in order that the foundations for such buildings or other structures may be properly designed, and also so that the problems and difficulties which will be encountered during the excavation of the foundation, may be accurately foretold.

15 It is an object of the present invention to provide simplified and improved apparatus for taking samples of the earth surface whereby a continuous sample may be secured of the various formations of the earth, which will accurately 20 disclose the character of the formation at any desired level or depth. By means of my improved apparatus, the hole is always cased from the top to bottom and, consequently, the danger of contamination of the samples to be taken by caving 25 ins and the like are eliminated.

This and other objects which will hereinafter be made apparent to those skilled in this particular art, I attain by means of this invention, one embodiment of which is described in the following specification and illustrated in the accompanying drawing, wherein:

Figure 1 is a view showing a cross section of the earth formations having an apparatus made in accordance with my invention extended there-in, a portion of the drilling apparatus being broken away for convenience of illustration;

Fig. 2 is an enlarged view in section of the upper end of the drilling apparatus;

Fig. 3 is an enlarged view in section showing the means of connecting the sample tube to the inner casing; and

Fig. 4 is an enlarged view in section of the lower end of the drilling apparatus and showing the setting of the sample tube on the drive shoe.

45 My improved apparatus for taking a continuous sample of the earth formations is composed of an outer casing 10 formed of a series of connected sections of drill pipe having a drive shoe 11 secured to the lowermost section thereof and 50 an inner casing 12 formed of a series of connected sections of pipe of somewhat smaller diameter than the diameter of the drill pipe used in the outer casing 10. The inner casing 12 terminates at its lower end in a thin-walled sample tube 13 55 which is supported at the bottom on an inwardly

projecting beveled shoulder 14 of the drive shoe 11 and is connected to the lowermost section of the inner casing by a reducing collar 13a.

A collar 15 having an internal buttress thread 5 16 is secured to the uppermost section of drill pipe making up the outer casing 10 and a driving head 17 is connected to the collar 15 for driving the outer casing 10 into the earth formations. In order that the inner casing 12 will be driven with the outer casing 10 and the sample tube 13 held 10 against the shoulder 14 of the drive shoe 11, an annular nut 18 having a buttress thread is threaded into the collar 15 into engagement with a collar 19 which is secured to the uppermost section of pipe of the inner casing 12 for protecting 15 the threads on said section. The nut 18 is provided with spaced upstanding projections 20 which may be readily engaged by a suitable tool inserted through the driving head to tighten the nut 18 and force the lower end of the sample tube 20 13 against the shoulder 14 of the drive shoe 11.

In taking a sample of the earth formations with my improved apparatus, a sample tube 13 having a length slightly in excess of the length of the sample desired to be taken is inserted in the outer casing 10, which is composed of a sufficient number of connected sections of drill pipe to provide a length of casing slightly less than the length of the sample tube, and the lower end of the sample tube is supported on the shoulder 14 30 of the drive shoe 11. The collar 15 is then threaded onto the uppermost section of the casing 10 and the nut 18 is threaded into the collar into engagement with the collar 19 which is then secured to the top of the sample tube 13. The 35 driving head 17 is then secured to the collar 15 and the apparatus so assembled is driven into the earth for the desired distance, approximately five feet, and since all the parts of the apparatus are tubular, a portion of the formations drilled 40 through rises within the sample tube 13.

After the apparatus has been driven to the desired depth, the nut 18 is removed and the sample tube 13 is pulled out of the outer casing 10 and the core of material in the interior thereof is 45 carefully removed and preserved. After the core has been removed from the sample tube, this tube is again inserted in the outer casing 10 and lowered into engagement with the shoulder 14 on the drive shoe 11. One or more sections of pipe, depending on the length desired, are then joined to each of the outer casings 10 and to the sample tube 13 and the collar 15 with the driving head 17 thereon is again secured to the uppermost 50 section of the casing 10 after which the nut 18 55

is threaded into place to hold the end of the sample tube 13 firmly in place against the abutting shoulder 14. The drilling apparatus is then driven through another predetermined distance of approximately five feet, after which the sample tube is again removed from within the casing 10 and the core of material therein is again taken therefrom.

10 The above cycles of operation are then continued until the drill hole has been driven to the depth desired.

15 From the foregoing description, it is apparent that with my improved apparatus the casing 10 remains in the drill hole at all times and, consequently, cave-ins of soft materials through which the hole has been drilled are prevented and since the sample tube 13 travels with the outer casing when it is being driven, a complete continuous sample of the earth formation is secured, the sections of which may be joined together to give 20 an exact replica of the cross section of the earth formation.

25 While I have described one embodiment of my invention, it is apparent that various changes and modifications may be made therein without departing from the spirit of my invention, and that devices such as trap valves now commonly used in sample boring when drilling through soft materials may be used with my improved sample 30 tube. It should be further understood that while I have shown the drill pipe sections as having square threads, any type of pipe suitable for drilling and having standard or other type of threads may be readily used, if desired.

35 Having thus described my invention, what I

claim as new and desire to secure by Letters Patent is:

1. Apparatus for use in taking test samples of earth formations comprising a casing, a drive shoe on one end of said casing, a sample tube positioned within said casing and supported on said drive shoe, a collar secured to the other end of said casing and having an internally threaded section, a drive head secured to said collar, and a nut threaded into said collar for engaging and holding said sample tube in position within said casing. 5

10 2. Apparatus for use in taking test samples of earth formations comprising a casing, a drive shoe on the bottom of said casing, a collar secured to the top of said casing and having an internal buttress thread, a drive head secured to said collar, a sample tube positioned within said casing and supported on said drive shoe and terminating at its upper end within said collar, and a nut 15 having a buttress thread cooperating with the buttress thread on said collar for engaging and holding the sample tube in position within said casing, whereby both the casing and the sample tube will be driven simultaneously. 20

25 3. Apparatus of the character described comprising a casing, a drive shoe secured to one end of said casing and having an inwardly projecting shoulder, a collar secured to the other end of said casing, a drive head connected to said collar, a sectional sample tube within said casing and supported on said shoulder and terminating at its upper end within said collar, and means threaded into said collar for holding said sample tube in contact with said shoulder. 30
